UNITED STATES PATENT OFFICE

2,210,816

DISCHARGE DEVICE

Lawrence D. Miles, Ballston Lake, N. Y., assignor
to General Electric Company, a corporation of
New York

Application February 2, 1939, Serial No. 254,156

6 Claims. (Cl. 250—27.5)

This application is a continuation-in-part of my prior application Serial No. 168,197, filed October 9, 1937.

The present invention relates to improvements in discharge devices which operate with an arc-like discharge. While not limited thereto, it is primarily applicable in connection with devices which employ a self-reconstructing cathode of extensive surface area. Such cathodes are best exemplified by the mercury pool and for that reason are referred to herein as "pool type cathodes." It should be understood, however, that the term "pool type cathode" as used herein and in the appended claims is not limited to liquid metals such as mercury, but is intended also to include solid substances which are capable of analogous use. Particular examples of such solid substances include cadmium and bismuth.

It is an object of the invention to provide means for confining the cathode spot to a desired region of the cathode surface. Such operation is especially desirable, for example, in connection with a metal-enclosed discharge device in which it is necessary to prevent the cathode spot from reaching and becoming fixed to the envelope wall.

The object specified in the foregoing is attained in accordance with the present invention by the use of means for producing a magnetic field which acts on the cathode spot or on the arc itself in such a way as to limit the motion of the spot.

The features which I desire to protect herein are pointed out with particularity in the appended claims. The invention itself, together with further objects and advantages thereof may best be understood by reference to the following description taken in connection with the drawings in which Fig. 1 represents partly in section a discharge device suitably embodying the invention; Fig. 2 is a transverse sectional view taken on line 2—2 of Fig. 1; Fig. 3 shows a modification of Fig. 1; Fig. 4 illustrates an alternative application of the invention; and Figs. 5, 6 and 7 are enlarged fragmentary sectional views showing in detail certain of the elements of Fig. 4.

Referring particularly to Fig. 1, there is shown a discharge device comprising an enclosing envelope 10 constituted of metal. This comprises a main cylinder forming the side walls of the envelope and a pair of transverse headers 11 and 12 which respectively close the envelope ends.

At the upper end of the envelope there are provided a pair of anodes 13 and 14 which are insulatingly supported from the envelope by means of glass-to-metal lead-in seals 16 and 17.

A barrier 19, interposed between the anodes, serves to separate their discharge paths and minimize the danger of arc-over between them.

At the lower end of the envelope and in co-operative relation with the anodes 13, 14 there is provided a pool-type cathode 21 comprising a quantity of mercury in direct contact with the header 11. A current connection to the cathode may be made by means of a heavy stud 22 attached to the header.

In order to initiate a discharge through the device, one may employ a make-alive electrode such as is indicated at 24. This may comprise, for example, a tapered rod of a semi-conducting material such as boron carbide having its tip 15 immersed in the cathode material. A lead-in connection 25 (Fig. 2) permits a starting potential to be applied to this electrode to initiate a cathode spot at the cathode surface. After the discharge is once started in this manner, it can be maintained by the alternate energization of the anodes 13 and 14.

In a device of the type described, wherein the discharge is of arc-like character, the cathode terminal of the discharge comprises a so-called cathode spot. This comprises a concentrated luminous area which tends to move rapidly over the cathode surface and which may under certain conditions become attached to the wall of the discharge envelope, resulting in disintegration 30 thereof. In order to prevent this latter occurrence, it is desirable to confine the cathode spot to a particular region of the cathode surface. My present invention comprises a novel means by which this result may be effectively accomplished.

In this connection there is shown outside the envelope 10 a magnetic structure 28 having its respective poles in direct contact with the surface of the header 11. This magnet may be permanently magnetized or separately excited by a D. C. field winding applied thereto. Within the envelope and cooperating with the magnet 28 there are provided auxiliary pole pieces 30 and 31 constituted of magnetic material. As shown, 45 these project above the cathode surface and are effective to confine the flux passing between the poles of the magnet 28 mainly to a direction which is parallel to the cathode surface; that is to say, transverse to the normal discharge path. 50

I have found that a magnetic field of this character, operating at the cathode terminal of an arc-like discharge, tends to control the motion of the cathode spot. This is apparently accomplished by the action of the magnetic field in 55

exerting a positive force on the cathode spot or on the components of the arm directly associated therewith.

The resultant motion of the cathode spot is 5 in a direction opposite from that which would be expected solely upon consideration of the reaction between the magnetic field and the current stream flowing between the cathode 21 and either of the anodes 13 and 14. That is to say, assuming 10 that the pole 30 of Fig. 1 is a north pole and the pole 31 a south pole, a cathode spot existing between the poles is caused to move in a direction toward the observer. This is true in spite of the fact that the arc-stream itself tends to move away 15 from the observer in accordance with the so-called "left hand rule" of electromagnetic reaction. I am not at the present time able to offer a complete explanation for this phenomenon, although I have frequently verified it in practice.

20 The action of the magnetic field above described obviously serves to prevent motion of the cathode spot in one direction only. In order completely to fix the spot, therefore, it is necessary to provide means for restricting its motion 25 in other directions. Such means may comprise, for example, a barrier such as is illustrated at 34 (Figs. 1 and 2). It is the function of this barrier partially to enclose the cathode spot and to prevent its motion in all directions except that 30 which is prohibited by the action of the magnetic field. In the particular form illustrated, which is to be taken as exemplary only, the barrier comprises a V-shaped member which projects partly above and partly below the mercury surface. The apex of the angle formed by the member points in the direction of the force exerted on the cathode spot by the magnetic field. Under these conditions, the cathode spot, when once established in the vicinity of the barrier, tends to 35 assume a position such as is indicated at 36. With this arrangement, while increases in the discharge current may tend to increase the dimensions of the cathode spot, they will not, for any normal condition, cause it to become dislodged from its confinement to a particular region 40 of the cathode surface. The barrier 34 may be constituted of any suitable refractory material of conducting or insulating character. I prefer, however, to form it of a metal such as tungsten, 45 or molybdenum which inherently exerts an anchoring action on a cathode spot in contact with it.

50

The magnetic structure may obviously assume many forms different from that shown in Fig. 1. 55 In Fig. 3, for example, there is illustrated an alternative arrangement wherein the header 11' is provided with reentrant pockets 38 and 39 adapted to receive the pole pieces of an externally arranged magnet 28'. The operation of this 60 structure is essentially similar to that of Fig. 1.

In Fig. 4 I have illustrated the application of my invention in connection with a discharge device having means for producing a holding arc and further means for segregating the discharge 65 space of the holding arc from the main body of the discharge envelope as described and claimed in my prior application Serial No. 168,197, above referred to. In this case there is provided a metal discharge envelope 40 which encloses only 70 a single main anode 41 adapted to receive a discharge from a cooperating cathode 42. With this construction the discharge, once initiated, must be maintained by a separate keep-alive device.

75 In the arrangement illustrated the keep-alive

means comprises a pair of auxiliary anodes 44 and 45 which are positioned above the surface of the cathode 42. As explained in my aforesaid prior application, it is desirable for certain uses to confine the discharge path of the holding arc 5 so that it is substantially segregated from the main discharge chamber. In the present case this object is partially accomplished by enclosing the anodes 44 and 45 in a shielding housing 47 which comprises an inverted cup-like 10 member consisting, for example, of quartz. This housing does not extend quite to the cathode surface but is provided with a metallic extension 48 (Fig. 5) consisting of molybdenum or a like 15 refractory metal.

The cross sectional outline of this extension is illustrated in Fig. 6, which comprises a section taken on line 6—6 of Fig. 5. From this figure it will be seen that the part 48 comprises a portion of generally cylindrical outline which has been 20 distorted so as to include a reentrant portion 49 forming a narrow slot or channel 50. In the operation of the device this channel is adapted to receive and retain the cathode spot in the position indicated at 51. The restricted opening 25 comprising the mouth of the channel thus provides substantially the only connection between the discharge path of the holding arc and the main discharge chamber.

The purpose of an arrangement such as that described is to assure that the cathode spot shall be initiated at the beginning of each current cycle at a point relatively close to the member 48 and remote from the metallic wall of the envelope 40. This is accomplished by virtue of the fact that the cathode spot of the holding arc tends to be retained at all times within the channel 50. Consequently, when the potential applied between the main anode 41 and the cathode 42 is favorable to a discharge, the cathode spot shown at 51 subdivides and creates another cathode spot corresponding to the main discharge arc at a point outside the slot 50 but in the vicinity of the shielded holding arc assembly. This latter cathode spot is extinguished at the end of each current cycle and is reestablished in approximately the same position at the beginning of the next current cycle. It is free to wander over the cathode surface, but is prevented from becoming fixed to the envelope wall by virtue of being cyclically "recalled" to the vicinity of the holding-arc assembly.

While the usual operation of the apparatus described is as explained in the foregoing, there is some tendency for the cathode spot 51 to be drawn out of the slot 50 and to be extinguished. In order to prevent this possibility, use is made of the magnetic spot retaining means previously described in connection with Fig. 1. This may comprise, for example, a permanent magnet indicated at 55 and having interior pole pieces 56 and 57 which function to confine the magnetic flux to the desired region. For proper operation with the arrangement shown in Figs. 4 to 6, the pole 56 should be a north pole and the pole 57 65 should be a south pole. Under these conditions the force exerted on the arc will be in such a direction as continuously to impel the cathode spot 51 into the slot or channel 50.

For some uses it is desirable to control the initiation of the discharge; that is to say, to provide means for determining whether or not a discharge shall take place during any given cycle. This is accomplished in the present connection by providing adjacent the opening of 75

the slot 50 an electrostatic control member or grid. In the arrangement shown, the grid comprises a perforate body 58 consisting of a heat-resisting conductor of good radiating properties, 5 for example, graphite. It is supported out of contact with the cathode 42 and may be supplied with a control potential by means of a suitable lead-in conductor (not shown in the drawings).

10 While I have described my invention in connection with particular structures, it will be understood that it may be employed with equal benefit in any case where it is desired to confine the cathode spot to a particular region of the 15 surface of a cathode of extended area. Numerous modifications may be made by those skilled in the art without departing from the invention. I, therefore, aim in the appended claims to cover all such equivalent variations as fall 20 within the true spirit and scope of the foregoing description.

What I claim as new and desire to secure by Letters Patent of the United States is:

1. A discharge device comprising an anode, a 25 pool type cathode, a barrier for restricting the motion of the cathode spot on the cathode surface, and magnetic means for impelling the cathode spot against the said barrier, thereby to maintain the spot in substantially fixed position 30 on the cathode surface.

2. A discharge device comprising an anode, a pool type cathode, a barrier extending above the cathode surface and providing a partial enclosure adapted to confine the cathode spot to a 35 particular region of the cathode surface, and means for producing a substantially unidirectional magnetic field parallel to the cathode surface in the vicinity of the barrier so as to prevent the cathode spot from leaving the said enclosure.

40 3. A discharge device comprising means forming a principal discharge space, means providing terminals for a discharge passing through said space, said terminal means including a pool-type cathode, one or more keep-alive electrodes 45 cooperating with the cathode surface for maintaining a holding arc adapted to facilitate the initiation of a discharge between said terminals,

shielding means substantially segregating the holding arc from the main discharge space except for the provision of a restricted opening in the shielded means at the cathode surface, and means for producing a magnetic field acting 5 transversely of the discharge path so as to prevent the holding arc cathode spot from leaving the said shielding means.

4. A discharge device comprising means forming a principal discharge space, means providing 10 terminals for a discharge passing through said space, said terminal means including a pool-type cathode, one or more keep-alive electrodes co-operating with the cathode surface for maintaining 15 a holding arc adapted to facilitate the initiation of a discharge between said terminals, and means for controlling the initiation of such a discharge, said last-named means including a shielding member substantially segregating the discharge space of the holding arc from the 20 principal discharge space except for the provision of a restricted passage between such spaces adjacent the cathode surface, means for producing a magnetic field in such relation to the path of the holding arc as to confine the holding arc cathode spot to a region of the cathode surface which is close to the opening of said 25 passage, and an electrostatic control means arranged in operative relation to the passage.

5. A discharge device comprising an anode, a 30 pool-type cathode, a barrier extending above the cathode surface and defining at least a partial enclosure, a portion of the wall of said enclosure being convergent toward a particular region of the cathode surface, and means for producing a magnetic field in such direction as to impel the cathode spot into the convergent portion of the enclosure, thereby to maintain the spot in a substantially fixed position on the said 35 particular region of the cathode surface. 40

6. A discharge device comprising an anode, a pool-type cathode, a V-shaped barrier extending above the cathode surface, and means for producing a magnetic field parallel to the cathode surface and in such direction as to impel the 45 cathode spot into the apex of the said V-shaped barrier.

LAWRENCE D. MILES.
